UNITED STATES PATENT OFFICE.

HENRY A. SCHWARZ, OF COLLEGE POINT, NEW YORK.

CLOTHESLINE DEVICE.

1,331,878.

Specification of Letters Patent. Patented Feb. 24, 1920.

Application filed February 24, 1919. Serial No. 278,669.

To all whom it may concern:

Be it known that I, HENRY A. SCHWARZ, a citizen of the United States, residing at College Point, in the county and borough 5 of Queens and State of New York, have invented certain new and useful Improvements in Clothesline Devices, of which the following is a specification.

My invention relates to improvements in 10 clothes lines, and has particular reference to means for automatically clamping the line to its pulley, when the line breaks for supporting the line and preventing the clothes from contacting with the ground.

Another object of the invention is to provide a device of the above mentioned character which is wholly automatic in operation, is simple in construction, strong and durable.

Other objects and advantages of the invention will be apparent during the course 20 of the following description.

In the accompanying drawing forming part of this specification and in which like 25 numerals are employed to designate like parts throughout the same:

Figure 1 is a side elevation of a device employing my invention;

Fig. 2 is a plan view of the pulley 30 equipped with the clamping means;

Fig. 3 is an end elevation of the same; and

Fig. 4 is a central vertical longitudinal section through the same.

In the drawings, wherein for the purpose 35 of illustration is shown a preferred embodiment of my invention, the numeral 5 designates a preferably grooved pulley, disposed within a preferably horizontal U-shaped frame 6. The closed end of this U-shaped frame is provided with a stationary clamping element 7 having an inclined face, as shown. The element 7 is rigidly secured to a screw 8 or other attaching element. It 40 is thus seen that the frame 6 may be rigidly secured to a post, wall or the like. The pulley 5 is pivoted upon a transverse element or pin 9 passing through the sides of the frame 6, as shown. An inverted U-shaped line 45 guide 10 is rigidly secured to the forward end of the frame 6, as shown.

The numeral 11 designates an inverted preferably U-shaped swinging clamping element, which straddles the pulley 5, and has the lower ends of its sides apertured for pivotally receiving the pin 9, and at its outer end this clamping element is provided with a transverse portion 12, the outer surface of which is serrated or milled for engagement with the line.

The numeral 14 designates a coacting pulley, pivoted within a frame 15, as shown at 55 16. The frame 15 is adapted to be rigidly secured to a second support, as is obvious.

Surrounding and engaging the pulleys 5 60 and 14 is a flexible endless element or line 17. This line has its upper run passed through the guide 10, and over and in contact with the serrated transverse element 12.

In the use of the apparatus, with the parts 70 assembled, as shown in Fig. 1, the clothes are attached to the lower run of the flexible endless element 17. When this element or line breaks, it is obvious that the weight of the clothes will tend to pull the lower 75 portion or run of the element 17 downwardly. This movement will cause the upper portion of the element 17 to swing the clamping element 11 downwardly, so that its serrated portion 12 has clamping engagement with the line held upon the inclined face of the clamping element 7. The line is thus supported at its upper end, and the clothes prevented from contacting with the ground, it being understood that the pulleys 80 5 and 14 are arranged at a suitable height 85 so that this is possible.

It is to be understood that the form of my invention herewith shown and described is to be taken as the preferred example of 90 the same, and that various changes in the shape, size and arrangement of parts may be resorted to without departing from the spirit of my invention or the scope of the subjoined claim.

Having thus described my invention, I 95 claim:

In apparatus of the character described, an approximately U-shaped frame provided at its closed end with an inclined clamping face, a pulley arranged within the frame, a pin connecting the pulley and 100

frame, an approximately U-shaped clamping element straddling the pulley and pivotally connected with the pin and having an inclined serrated clamping face, an upwardly standing guide connected with one end of the frame, a flexible endless element engaging the pulley and passing through the guide and contacting with the inclined serrated clamping face, and a second pulley

supporting the opposite end of the endless element.

In testimony whereof I affix my signature in presence of two witnesses.

HENRY A. SCHWARZ.

Witnesses:

EUGENE WEBER,

JOSEPH KOENIG.
